UNITED STATES PATENT OFFICE.

JUSTUS A. TRAUT, OF NEW BRITAIN, CONNECTICUT.

DESIGN FOR A CLASP.

SPECIFICATION forming part of Design No. 21,400, dated March 15, 1892.

Application filed February 17, 1892. Serial No. 421,885. Term of patent 7 years.

To all whom it may concern:

Be it known that I, JUSTUS A. TRAUT, a citizen of the United States, residing at New Britain, in the county of Hartford and State of Connecticut, have invented and produced a new and original Design for Clasps, of which the following is a specification, reference being had to the accompanying drawings, forming a part thereof.

5 In the drawings, Figure 1 is an edge view of a clasp embodying my design, which is shown in the plan or side view, Fig. 2.

The leading feature of my design consists

in two corresponding figures M and N, located one within the other, the larger figure joining representations of elongated loops, as 2 and 4, respectively, located one at each end of said figure M.

Having thus described my design, I claim—

10 The design for a clasp, herein shown and described, substantially as set forth.

JUSTUS A. TRAUT.
